UNITED STATES PATENT OFFICE.

EDWARD C. MODES, OF CICERO, INDIANA, ASSIGNOR TO THE MODES GLASS COMPANY, OF SAME PLACE.

DESIGN FOR A BOTTLE.

SPECIFICATION forming part of Design No. 28,483, dated April 19, 1898.

Application filed February 8, 1898. Serial No. 669,597. Term of patent 14 years.

To all whom it may concern:

Be it known that I, EDWARD C. MODES, a citizen of the United States, residing at Cicero, in the county of Hamilton and State of Indiana, have invented and produced a new and original Design for Bottles, of which the following is a specification, reference being had therein to the accompanying drawings, in which—

10 Figure 1 is a side elevation of the bottle. Fig. 2 is an edge elevation, partly in section. Fig. 3 is a bottom plan, and Fig. 4 is a perspective view.

15 A is a conoidal body portion having an oval base B. This body portion in side elevation has the appearance of a truncated ovoid, having its greatest diameter above the base-line.

C is a round neck projecting upward from the body.

The oval base B is concave, as at D, and 20 provided with the knobs or projections E, arranged around its border and in the center of the concave.

The leading feature of the design is the conoidal body having the oval base and forming the truncated ovoidal appearance in side elevation.

What I claim as my invention is—

The design for a bottle, substantially as herein shown and described. 30

In testimony whereof I affix my signature in presence of two witnesses.

EDWARD C. MODES.

Witnesses:

CHARLES M. TURNER,
ELAH OVERMYER.
